UNITED STATES PATENT OFFICE.

GEORGE E. RYAN, OF NEW YORK, N. Y.

AUTOMATIC SAFETY APPARATUS FOR RAILWAYS.

No. 866,521.

Specification of Letters Patent. Patented Sept. 17, 1907.

Application filed September 27, 1906. Serial No. 336,392.

To all whom it may concern:

Be it known that I, GEORGE E. RYAN, a citizen of the United States, and a resident of the city of New York, (Laurel Hill, borough of Queens,) in the county 5 of Queens and State of New York, have invented a new and Improved Automatic Safety Apparatus for Railways, of which the following is a full, clear, and exact description.

This invention relates to automatic safety devices, 10 such as used on railways for preventing accidents or collisions.

The invention contemplates the use of automatically-operated track devices which are set by the trains as they pass; in this way, each train as it proceeds maintains a track device in a set position at a suitable distance in its rear. A following train cannot pass this track device without having its power automatically cut off. In this way rear end collisions are effectually prevented.

20 The invention consists in the construction and combination of parts to be more fully described hereinafter and particularly set forth in the claims.

Reference is to be had to the accompanying drawings forming a part of this specification, in which similar 25 characters of reference indicate corresponding parts in all the figures.

Figure 1 is a side elevation of the forward portion of a locomotive, illustrating the manner in which my invention is applied thereto; Fig. 2 is a vertical section 30 taken through the dry pipe and a portion of the locomotive boiler and illustrating the manner in which the invention operates to cut off the supply of steam to the engine cylinder; Fig. 3 is a plan showing a section of track equipped with my track devices, the same being 35 a diagrammatic view; Fig. 4 is a vertical section through one of the track devices and taken transversely of the track; Fig. 5 is a horizontal section through the case of the track device on the line 5—5 of Fig. 4; Fig. 6 is an elevation of a valve which is controlled by the 40 track devices, and which, in turn, controls the locomotive; this view also shows a trip device which operates the valve; Fig. 7 is a vertical cross section of the aforesaid valve and trip device, certain parts being broken away; this view is a section on line 7—7 of Fig. 6; Fig. 45 7^a is an end elevation showing details of construction of the valve which is illustrated in Figs. 6 and 7; Fig. 8 is a plan of a contact device showing a portion of the rail near which the same is placed; and Fig. 9 is a vertical section through a contact device, a plurality of which I 50 distribute along the track and which afford means for controlling the track devices.

Referring more particularly to the parts, 1 represents a locomotive of any suitable construction, having the usual dry-pipe 2 which extends longitudinally of the 55 boiler in the upper portion thereof. In this dry-pipe I place a gate valve 3, as indicated in Figs. 1 and 2. A

bonnet 4 for this valve passes through the boiler shell, as indicated, and receives the gate 5 of the valve. The upper portion of this bonnet 4 is formed into the lower head of a cylinder 6 through which passes a piston rod 60 7 which is attached to the gate, as indicated, the upper extremity of said piston rod carrying a piston 8, as shown.

Through the upper head 9 of the cylinder a pipe 10 leads, which pipe passes downwardly at the side of the 65 locomotive so as to communicate with a valve or cock 11 placed beneath the locomotive, as indicated most clearly in Fig. 1. This valve is supported on suitable brackets 12 attached to any part of the frame 13, as indicated in Fig. 6. The valve consists of a cylindrical 70 casing or barrel 14, in the interior of which there is a rotatable plug 15, said plug having stub-shafts 16 which are rotatably mounted in the heads 14^a of the valve 11. The pipe 10 passes to the upper side of the wall of the barrel 14, as indicated in Fig. 5. Near this point there 75 is arranged a supply pipe 17 which leads rearwardly and connects with the air reservoir of the engine. On the opposite side of the pipe 10 an exhaust pipe 18 is disposed, which communicates with the atmosphere.

Rigidly attached to the shaft 16 there is a trip 80 device 19, which simply consists of a flat plate which hangs downwardly, as indicated in Fig. 1 and normally maintains the plug 15 in the position shown in Fig. 7. In this position a port 20, in the side of the plug 15, opens communication between the pipes 10 and 18, 85 so that the upper end of the cylinder 6 is open to the atmosphere. A second port 21 is formed in the side of plug 15 and is in such a position that if the trip 19 is moved toward the right, communication will be opened between the pipes 10 and 17. In the pipe 17 above 90 the valve 11 there is provided a check-valve 17^a which opens toward the reservoir with which the pipe 17 connects. This valve has a depending stem the lower end whereof rests against the lower part of the wall of the port 21. The wall of this port is curved to concave as shown so that the stem does not prevent rotation of the plug 15; the rotation of the plug simply raises or lowers the valve stem. The arrangement is illustrated in Fig. 7. By rotating the plug in a left-hand direction the plug will operate to raise the check 100 valve from its seat 17^b. By this rotation the port 21 also opens communication from the pipe 10 to the pipe 17. When this occurs, air from the reservoir of the engine is admitted into the upper end of the cylinder 6, operating to force the piston 8 downwardly and close 105 the gate valve 3. In this way, the flow of steam to the cylinders through the drive pipe is completely cut off, so that the engine will come to a stop.

I provide a plurality of track devices 22, the construction of which is very clearly illustrated in Figs. 4 110 and 5. This track device is preferably composed of a box 24 in which there is located an electro-magnet

or solenoid A and an electro-magnet or solenoid B disposed oppositely to each other, and in substantial axial alinement as indicated. Within each of the coils of these magnets, magnet cores 25, 26 are provided, the core 26 being arranged in connection with the magnet A. This core is connected, by means of a suitable link or piston 27, with a cam 28 pivotally mounted on a shaft 29, the said cam having substantially the form of a heart, the small end whereof is cut away as indicated. In this way an elevated cam face 30 is provided and a notch 31, at which the cam face is depressed or approaches toward the axis 29. The cam 28 is provided with a counterweight 32 which normally tends to maintain the cam in an inoperative position; that is, with the notch 31 disposed at an elevated point. On the cam face 30 rests a roller 33 which is pivoted upon a pin 34 which projects upwardly through a suitable opening 35 formed in the cover of the box 24. When the cam 28 is occupying its normal position, the roller 33 occupies the notch 31 and the pin 34 does not project above the road-bed or cover of the box 24. The edge of this opening is provided with an upwardly projecting lip 35^a and the pin 34 formed with an enlarged head 35^b the under side whereof is formed with a groove 35^c. When the track device is in its set position, the pin 34 projects from the box as shown. When in the inoperative position, the head of the pin seats on the box with the lip 35^b received in the groove 35^c. On the side of the cam 28 which lies opposite the electro-magnet A, the said cam is provided with an abrupt shoulder 36, and with this shoulder co-operates a bell crank shaped catch 37 which is pivotally mounted at 38 on the box, and to the upper portion of this catch 37 the core of the magnet B is connected by a link 25^a. The lower portion of the catch 37 is provided with a laterally projecting toe 39. Beneath this toe 39 a spring 40 is placed, which thrusts upwardly and normally maintains a dog 41 on the catch in engagement with the shoulder 36. When in this position the weight 32 evidently operates to maintain the shoulder 36 against the dog 41, so that the cam 28 is maintained in equilibrium. As indicated, the track device is disposed transversely between the rails 42 of the track; that is, the axes of the magnets A and B are disposed at right angles to the rail. On the upper side of the dog 41 I provide an upwardly projecting rib 41^a. In order to enable the track device to close signal circuits automatically, the shaft 29 is provided with a rigid contact cam 29^a co-operating with contacts 29^b and 29^c. I provide automatic means whereby the passing of the train controls the operation of the track devices. In Fig. 3 I illustrate an electric circuit arrangement for this purpose. In reading this drawing, it should be understood that the dimensions taken longitudinally of the track are greatly shortened, for the purpose of illustration, and it should be remembered that the track devices are disposed at a suitable distance apart, say a half-mile or a mile. At suitable points along the track I provide batteries 43. With each of these batteries a circuit *a* is formed, passing through contact devices 44 and through the aforesaid electro-magnets A, back to the battery; a conductor 45 carrying the current to the electro-magnet, while the conductor 46 returns the same.

In Fig. 3 I represent three of the track devices, indi-

cated respectively by the numbers 47, 48, 49. At the points 50 the conductors 45 of the circuits *a* are connected with conductors 51 which lead to the electro-magnets B of an adjacent track device; the opposite end of the coil B being connected through a conductor 52 with one of the rails along which the current returns through the point 53 where connection is had to a conductor 54 which connects with the return wire 46 at the point 55. It should be understood that the train is supposed to pass from the right to the left as viewed in Fig. 3. When the wheels of the locomotive pass over the contact devices 44, the circuit *a* becomes closed. In this way the electro-magnet A of that circuit becomes energized and its core 26 is drawn inwardly so as to set the track device in the relation shown in Fig. 4; that is, with the pin 34 projecting upwardly. At the same time that the current is flowing in this circuit *a*, a parallel circuit is formed through the wires 51, 52, etc., which may be considered to be a circuit *b*. This circuit extends back on the track to the track device 56 which has just been passed by the locomotive. In this way the electro-magnet B of this rear track device becomes energized and the core 25 thereof is drawn inwardly. In doing so, the dog 41 releases the shoulder 36 and allows the counterweight 32 to move the cam 28 down in its normal position, allowing the pin 34 to become depressed. In this way as the engine proceeds, it continually sets the successive track devices over which it passes and continually unsets or throws into an inoperative position, the track devices in the rear. From this arrangement it follows that there will always be, in the rear of a moving train, a set track device. To explain more specifically the mode of operation when a train passes, it may be said that when the locomotive reaches the contact devices 44 which are disposed in connection with the track device 47, the circuit *a* will be closed through the electro-magnet A of the track device 47, which will operate to set this track device in the manner described above. This track device will remain set until the engine arrives at the contact devices 44 in connection with the track device 48. When the circuit *a* is closed at this point, the magnet B of the track device 47 becomes energized and the track device unset. At the same time the magnet A of the track device 48 is energized when this track device becomes set, and so on. The construction of the contact devices 44 is very clearly shown in Figs. 8 and 9. Each contact device comprises a base 56 the central portion whereof has the form of a cup 56^a above which there is placed a depressible cap or head 57, the said cap being pivoted at 57^a. This cap 57 is formed on its under side into a contact button 58 while the cup 56^a is provided with a centrally disposed boss carrying an insulating plate 59. The sections 45^a and 45^b of the wire 45 which constitute the conductor 45 are attached respectively to the plate. Within the device a helical spring 61 is arranged which normally maintains the cap 57 in an elevated position, so that the contact is normally open. The cap 57 is provided with a laterally projecting rail-plate 62 which has a toe 62^a engaging the under side of the head of the rail 63. The entire track device is inclosed in a suitable case 60, leaving an opening 60^a through which the rail-plate projects. It should be understood that the wires 45^a and 45^b are insulated from all parts of the

contact device so that the circuit may be closed by depressing the cap. It should be understood also that the dry-pipe 2 connects with the cylinders 64 of the locomotive, in the usual manner, so that when the gate 5 valve 3 is closed, the supply of steam to the cylinders is effectually cut off. The trip plate 19 projects into the path of the pins 34 of the track devices when they are set, which projects upwardly as indicated in Fig. 1. It will be observed that the lower end of the cylinder 6 is closed, from which arrangement it follows that when the piston 8 is forced downwardly, the air in this part of the cylinder will be compressed. The pressure of this air affords means for returning the piston to its normal upright position to re-open the gate valve 3. 10 The upward movement of the gate is also assisted by the pressure of the steam of the dry-pipe upon its under side.

I provide an arrangement whereby the rearward motion of the trip-plate will operate to rotate the plug 15 20 while a movement in the opposite direction will not affect it. For this purpose the arms 19^a of the trip 19 are formed into hubs 19^b as illustrated in Fig. 7^a; each of said hubs presents a shoulder 19^c on its rear side, which normally abuts against a similar shoulder 16^a 25 which is formed on the projecting end of the corresponding stub-shaft 16; on the forward side the material of the shaft and the hub is cut away to form a gap 19^d. From this arrangement a motion of the trip 19 toward the right, that is, toward the rear, will rotate the plug by 30 means of the engaging shoulders 16^a and 19^c, but a motion of the trip forward will not affect the plug by reason of the gap. Hence, it is possible for the locomotive to back over one of the track devices without affecting the valve 11. In order to return the trip to 35 its normal position after it has been struck by a track device when the locomotive is backing, I provide a leaf spring 14^b as illustrated in Figs. 6 and 7, which is attached to the barrel 14 of the valve and touches at its lower end against the trip 19. This spring gives

forwardly when the trip is moved in that direction and 40 returns the trip afterwards.

The pipe 10 has a branch connection 10^a which leads rearwardly to the train service pipe for the air-brakes so that when the power is shut off, the brakes will be automatically applied also. The check valve 17^a 45 effectually prevents any leakage from the reservoir to the valve 11 when the valve is closed.

In order to facilitate the guiding of the pin 34, I provide a friction roller 34^a, carried by the case; the face of this roller rests against the side of the pin and guides 50 the pin as its rises or descends in the opening 35.

Having thus described my invention, I claim as new, and desire to secure by Letters Patent:

1. In a track device, in combination, a pin adapted to project into the path of a trip, a cam controlling the position of said pin, an electro-magnet having a core connected with said cam, a catch for maintaining said cam in a set position, and an electro-magnet controlling said catch to release said cam. 55
2. In a track device, in combination, a pin adapted to project into the path of a trip, a cam disposed beneath said pin and controlling the position thereof, an electro-magnet having a core, a link connecting said core with said cam, means tending to hold said cam in an inoperative position, a catch engaging said cam and affording means 60 for maintaining the same in a set position, and an electro-magnet for releasing said catch. 65
3. In a track device, in combination, a pin adapted to project into the path of a trip device, a cam having a cam face supporting said pin, an electro-magnet having a core, a link connecting said core with said cam, said cam having an abrupt shoulder formed on the side thereof, a spring-pressed catch engaging said shoulder and affording means 70 for supporting said cam, a counterweight carried by said cam and tending to maintain said shoulder against said catch, and an electro-magnet having a core connected with said catch. 75

In testimony whereof I have signed my name to this specification in the presence of two subscribing witnesses.

GEORGE E. RYAN.
